CLAIM

(21) Appl. No.: **29/545,150**

The ornamental design for the male component of enteral feeding connector, as shown and described.

(22) Filed: **Nov. 10, 2015**

DESCRIPTION

(30) **Foreign Application Priority Data**

May 18, 2015 (EM) 002702597

(51) **LOC (10) Cl.** **24-02**

FIG. 1 is a top perspective view of an enteral feeding connector male component showing my new design, the opposite top perspective view being identical;

(52) **U.S. Cl.**

FIG. 2 is a front view of the male component of enteral feeding connector of FIG. 1;

USPC **D24/129**

FIG. 3 a back view of the male component of enteral feeding connector of FIG. 1.

(58) **Field of Classification Search**

FIG. 4 is an elevational end view of the male component of enteral feeding connector taken from the right-hand side of FIG. 2;

USPC D24/107, 108, 112, 127, 129; D23/262

FIG. 5 is an elevational end view of the male component of enteral feeding connector taken from the left-hand side of FIG. 2;

CPC A61M 39/10; A61M 39/1011

See application file for complete search history.

FIG. 6 is a top view of the male component of enteral feeding connector of FIG. 2; and,

(56) **References Cited**

FIG. 7 is a bottom view of the male component of enteral feeding connector of FIG. 2.

U.S. PATENT DOCUMENTS

The broken lines immediately adjacent the shaded areas represent the bounds of the claimed design, while all other broken lines are directed to portions of the article excluded from the claim. The broken line disclosure forms no part of the claimed design.
